UNITED STATES PATENT OFFICE.

ANTON HULSMANN, OF SAN FRANCISCO, CALIFORNIA.

AMUSEMENT DEVICE.

1,421,238.

Specification of Letters Patent. Patented June 27, 1922.

Application filed June 17, 1921. Serial No. 478,382.

To all whom it may concern:

Be it known that I, ANTON HULSMANN, a citizen of Germany, residing at San Francisco, in the county of San Francisco and 5 State of California, have invented new and useful Improvements in Amusement Devices, of which the following is a specification.

This invention relates to amusement devices and has particular reference to a device 10 designed for entertainment and exercise and comprises a main frame upon which are supported a plurality of vertical standards holding a series of air balloons adapted to be inflated by the blowing action of participants engaged in the blowing contest, whereby the first participant accomplishing the bursting of one of the balloons in the shortest time is acclaimed the victor over the other competitors.

20 This device has various novel details tending to simplicity and cheapness of construction, which are desirable in an amusement device. Furthermore, the construction is such that the device can be produced at a 25 modest cost, is highly attractive in appearance and entertaining, positive in action, and extremely sanitary.

Other objects and advantages will be apparent during the course of the following description.

In the accompanying drawings forming a part of this specification and in which like numerals are employed to designate like parts throughout the same.

35 Fig. 1 is a perspective view of the device, Fig. 2 is an enlarged sectional view of the same, showing the air outlet port closed.

Fig. 3 is a fragmentary sectional view of the device with the air outlet port open.

40 Fig. 4 is a sectional view of the rubber tubing and its mouth piece, forming part of this invention,

Fig. 5 is an enlarged perspective view of the control mechanism and its associated parts,

45 Fig. 6 is a side elevation of one of the balloons shown inflated and mounted on the standard, and

Fig. 7 is a side elevation of one of the 50 balloons prior to inflation or after it has been bursted.

In the accompanying drawings wherein for the purpose of illustration is shown a preferred embodiment of my invention, the 55 letter "A" designates a table or conventional

support, upon which is mounted a frame designated as a whole by the numeral 8, which frame includes a top wall 9, a front side wall 10 and end sills 11 and 12 respectively. Preferably secured to the top wall 9 is a 60 longitudinally extending strip 13 which serves as a support and upon which are received a plurality of vertical standards 14. Each standard is provided with a central bore 15 in which is received a length of pipe 65 16. Detachably mounted on the upper extremity of the pipe 16 is a nipple 17, while secured to the lower extremity of the pipe 16 is the upper end of a T 18, and threaded to the lower end of the T 18 is a short pipe 19. 70 Formed in the strip 13 and the top wall 9 are openings 20 through which the short pipe 19 extends. For the purpose of securing the short pipe beneath the lower surface of the wall 9 I have provided a nut 21 and 75 the usual washer 21'. Positioned parallel to the top wall 9 and secured in the inlet openings 22 of the T 18 is a tube 23. This tube is adapted to extend through the base part of the vertical standard 14 and has 80 connected thereto at its free end the end of a flexible tubing 24 preferably made of soft rubber. As shown to advantage in Figures 1 and 4 each of the tubes is provided with a sanitary mouth piece 25 preferably made of 85 straw or paper and so positioned on the end of the tubing that it can be readily detached or applied thereto.

While I have described the construction of but one of the standards, it is to be understood that the other standards and associated parts are of like construction and need not be specifically described. On each nipple 17 an air balloon "B" is detachably secured, and I prefer to make these balloons of various colors.

From a consideration of the construction of the standards and the means for inflating the balloon, it will be apparent that air blown through the tubing 24 into the 100 tube 23 will, due to the hollow formation of the T 18 and the disposition of the pipe 16 and the short pipe 19, either pass upwardly through the pipe 16 or downwardly through the short pipe 19. The mechanism 105 for controlling the direction of the passage of air forms an important feature of this invention and the same will be hereinafter fully described.

Journalized in the end sills 11 and 12 are 110

the extremities of a cross bar 26. This cross bar is positioned parallel to the top wall 9 and is freely movable in the respective end sills upon manual movement of a 5 control handle 27. As shown to advantage in Figure 5 the control handle is inserted in the opening 28 of a second T 29 which embraces the cross bar 26 and is fixed thereto and rotatable therewith. Disposed in 10 parallel relation to the control handle 27, are a plurality of blocks 30 and corresponding in number to the number of vertical standards employed. Each of these blocks 30 is provided with an upper level surface, upon which surface adjacent its inner end is suitably secured a cushion element 31 preferably made of rubber, while mounted in the side wall 32 of each block is a stop 33. In close proximity to the side wall 32 15 of each block 30 and secured to and rotatable with the cross bar 26, is a flanged collar 34. Formed on the collar 34 is a lifting finger 35 which is adapted to contact with the stop 33. As shown to advantage in Figures 2 and 3 it will be apparent that downward movement of the handle 27 by the operator will cause the finger 35 to engage the stop 33 and thus the inner end of the block 30 will be raised while the outer end upon 20 which the cushion element is disposed will be lowered. When the block 30 is in this position it will be obvious that air entering the tube 24 through the blowing action of the participant, will pass into the standard 25 and be expelled from the pipe 19. On the other hand when it is desired to direct air into the pipe 13 the control arm is moved, upwardly, by the operator, and the cushion block engages the lower extremity of the 30 pipe 19 and the air is directed through the pipe 16 to the balloon secured on the end of the standard.

In order to positively assure the disengagement of the cushion element from the 45 end of the pipe 19, I propose to suitably secure a counter weight (not shown) on the lower end of the control arm. When the operator wishes the participant to start the counter weight will be lifted by upward 50 movement of the control arm 27.

The operation of my device is as follows:—

The participants engaging in the contest assemble on the outside of the frame 8, 55 and each participant either selects a tube to be either designated by a certain numeral, or selects a certain color of balloon that he proposes to inflate. The operator then announces that the contest is started 60 and immediately throws the control arm 27 from the position shown to advantage in Figure 1 to the position shown to advantage in Figure 2.

It will be apparent that the inflow of 65 air will be forced upwardly through the

pipe 16 and will cause the air balloon mounted thereon to be inflated. Since the lung power of all individuals is not the same it will be obvious that one of the balloons will be bursted sooner than the remainder, and accordingly, upon the bursting of one of the balloons the victor in the contest will be recognized. Immediately after the bursting of a balloon occurs the operator releases the arm 27 and by virtue of 70 the counter weight causing the downward movement of the control arm the cushion element 31 will be disengaged from the end of the pipe 19 and the air will pass through the latter. Thus there will be a saving in 75 the number of balloons employed for it will be apparent that only one balloon will be bursted. Another balloon is then substituted for the bursted one and the game can begin again. 80

While I have shown a certain number of standards and balloons, it is to be understood that a plurality of standards can be employed and it is to be further understood that the form of my invention herewith 90 shown and described is to be taken as a preferred example of the same, and that various changes in the shape, size and arrangement of parts may be resorted to without departing from the spirit of the invention or 95 the scope of the subjoined claims.

Having thus described my invention, I claim:—

1. A device of the character described, comprising a supporting frame, having end sills and a top board, a plurality of standards mounted on said frame, each of said standards being provided with a central bore and having an air balloon mounted thereon, a sectional pipe secured in said bore, a T 100 element for holding the sections in a fixed position, means connected to said T element and adapted to supply air to said pipe, and mechanism positioned within said frame and operable from the outside thereof for controlling the supply of air to said pipe, said mechanism including a cross bar journaled in the sills of said frame, blocks secured to said cross bar, and a control arm connected to said cross bar and adapted to actuate the 105 same.

2. In a device of the character described, the combination with a frame having vertical tubular standards mounted thereon adapted to support a plurality of air balloons, of means for conveying a supply of air to said standards, mechanism connected to said frame for controlling the supply of air entering and exhausting from said standards, said mechanism including a cross bar 110 journaled in the sills of said frame, blocks secured to said cross bar, cushion elements secured on the upper surfaces of said blocks, and a control arm connected to said cross bar, whereby upon its actuation said cushion 115 120 125 130

elements are thrown into and out of engagement with the lower extremities of said standards.

3. In a device of the character described, 5 the combination with a frame having vertical tubular standards mounted thereon adapted to support a plurality of air balloons, of means for conveying a supply of air to said standards, mechanism connected 10 to said frame for controlling the supply of air entering and exhausting from said standards, said mechanism including a cross bar

journaled in the sills of said frame, blocks secured to said cross bar, cushion elements secured on the upper surfaces of said blocks, 15 a control arm connected to said cross bar, and means positioned on said cross bar and said blocks, whereby upon the actuation of said control arm the cushion elements on said blocks are disengaged from the lower 20 extremities of said standards.

In testimony whereof affix signature.

ANTON HULSMANN.
